UNITED STATES PATENT OFFICE.

FREDERICK HENRY ROYCE, OF DERBY, ENGLAND.

ELECTRIC IGNITER.

1,030,432.

Specification of Letters Patent.

Patented June 25, 1912.

Application filed November 18, 1911. Serial No. 661,018.

To all whom it may concern:

Be it known that I, FREDERICK HENRY ROYCE, a subject of the King of Great Britain and Ireland, residing at Nightingale 5 Road, Osmaston Road, Derby, in the county of Derby, England, have invented certain new and useful Improvements in Electric Igniters, of which the following is a specification, reference being had therein to the 10 accompanying drawing.

This invention relates to that type of high-tension distributor in which the current is distributed to the sparking plugs of the several cylinders in the required order 15 by rotating an electrode connected to the source of supply of electric current sufficiently near to other electrodes connected to the sparking plugs to allow the current to pass between said electrodes in the form of 20 sparks, and it has for its object to provide more efficient and convenient forms of electrodes than at present obtains and to enable said electrodes to be easily and readily adjusted. I attain this end by the construction 25 shown in the accompanying drawings which illustrate—by way of example—a distributor for a six-cylinder engine.

In said drawings:—Figure 1 is a view in front elevation of the distributor, Fig. 2 is 30 a view in sectional side elevation thereof, Figs. 3 and 4 are broken sectional views—on an enlarged scale—showing one of the electrodes and terminals, and Figs. 5 and 6 are broken views—on an enlarged scale—of 35 the electrodes.

Throughout the views similar parts are marked with like letters of reference.

The ring-shaped body A of the distributor is constructed of suitable non-conducting 40 material and carries six terminals D to which the leads to the sparking plugs are connected and six electrodes C, said terminals and electrodes being equally spaced around the circumference of the ring. The 45 body portion A, together with the electrodes C, is held stationary in any approved manner. The electrodes each consist of a rod of suitable conducting material the sparking end of which is shaped to form a line or 50 knife edge. The preferred method of making this line or knife edge is to bevel the two opposite sides of the end of the electrode to form a groove in said knife edge and to lay a piece of platinum or other suitable wire 55 E into said groove and solder it therein, working the edges of the groove over the

wire in such a manner as to leave a portion of the circumference of the wire bare.

Each of the electrodes C is held in position in the ring-shaped body A by a split sleeve F which is recessed into the ring and retained there by a sleeve nut H which is screwed into the ring and locked thereto by a cap M. A pin d is carried by the electrode C which engages with grooves formed by 60 two of the splits in the sleeve F, said pin and grooves being so located in relation to one another and to the wire E that said wire lies parallel to the axis of the distributor. 65

Each of the electrodes C is in electrical contact with the sleeve F from which current is carried to its respective terminal D by means of a spring plunger N mounted in an axially arranged recess d' in the base 70 of the terminal and kept in contact with the sleeve F by means of a spiral spring O. The base of the terminal D is recessed into the ring-shaped body A and attached thereto by means of the two screws t. 75

The revolving electrode R is carried by a piece P made of suitable non-conducting material and driven at a suitable speed by gearing from the crank-shaft of the engine. The sparking point of the electrode R is of 80 similar shape and is formed in a similar manner to that of the electrodes C, but the knife-edge-shaped point formed by the embedded wire S instead of being straight is curved to an arc of a circle whose center is 85 the axis about which the electrode revolves. The electrode R is secured in the part P by screws p p which also serve to make an electrical connection between the said electrode R and a plate p' with which the terminal T 90 connected to the secondary winding of the coil contacts. The terminal T is carried by the cover W of the distributor which is of any suitable non-conducting material. Current is carried from the terminal T to the 95 contact plate p' by means of a plunger V which is kept in contact with the plate p' by a spring v, said plunger bearing in a bush X which is also in contact with said terminal. To prevent the plunger V from 100 being turned on its axis by the rotation of the plate p' it may be made of a square section and the bush X shaped to correspond. It will be seen that the line sparking point S of the electrode T moves by the rotation 105 of the part P in a path at right angles to the line sparking point E of the electrode C.

110

which results in the sparking being localized at a point which moves along the circumference of the line sparking point S as the electrode T revolves.

5 The air gap between the electrodes is adjusted by removing the cap M and pressing the electrode C in by hand until the wire E is just clear of the wire S. The tongues formed on the sleeve F by the splits are set 10 slightly inward in order to hold the contact pieces firmly by friction in any position longitudinally to which they may be adjusted. A balance weight Y is provided on the revolving part P at a point diametrically 15 opposite to the electrode R.

What I claim as my invention, and desire to secure by Letters Patent is:—

1. In an electric igniter, the combination, with a stationary body portion, and a rev- 20 oluble block; of electrodes carried by the said body portion and block and provided with tapering knife-like end portions arranged at a right angle to each other and having grooves in their ends, and sparking 25 wires secured in the said grooves and forming the apices of the said tapering end portions.

2. In high-tension distributors for electric ignition systems for internal combustion engines, the combination of a fixed electrode and a rotating electrode, the sparking points of which have a knife-edge or line formation and said points being relatively arranged so that one lies or moves at right 35 angles to the other, a split sleeve carried by the body of the distributor and adapted to carry the fixed electrode, and means for contracting said split sleeve to grip said electrode, as set forth.

40 3. In high-tension distributors for electric ignition systems for internal combustion engines, the combination of a fixed electrode and a rotating electrode, the sparking points of which have a knife-edge or line formation and said points being relatively arranged so 45 that one lies or moves at right angles to the other, a split sleeve carried by the body of the distributor and adapted to carry the

fixed electrode, means for contracting said split sleeve to grip said electrode, and means for retaining the electrode in its correct position relative to the axis of the distributor, as set forth. 50

4. In high-tension distributors for electric ignition systems for internal combustion engines, the combination of a fixed electrode and a rotating electrode the sparking points of which have a knife-edge or line formation and said points being relatively arranged so that one lies or moves at right 55 angles to the other, a split sleeve carried by the body of the distributor and adapted to carry the fixed electrode, means for contracting said split sleeve to grip said electrode, means for retaining the electrode in its correct position relative to the axis of the distributor, a terminal carried by the body of the distributor, and a spring contact for establishing contact between the said terminal and the split sleeve, as set forth. 60

70 5. In high-tension distributors for electric ignition systems for internal combustion engines, the combination of a fixed electrode and a rotating electrode the sparking points of which are formed by a piece of wire and 75 which are relatively arranged so that the sparking point of the rotating electrode lies or moves at right angles to that of the fixed electrode, a split sleeve carried by the body of the distributor and adapted to carry the fixed electrode, means for contracting said split sleeve to grip said electrode, means for retaining the electrode in its correct position relative to the axis of the distributor, a terminal carried by the body of the distributor, and a spring contact for establishing electrical contact between said terminal and the split sleeve, as set forth. 80

85 In testimony whereof I have hereunto signed my name in the presence of two sub- 90 scribing witnesses.

FREDERICK HENRY ROYCE.
